UNITED STATES PATENT OFFICE

WILLIAM R. MORSE, OF CHICAGO, ILLINOIS.

LETTER-OPENER.

SPECIFICATION forming part of Letters Patent No. 414,886, dated November 12, 1889.

Application filed January 21, 1889. Serial No. 297,072. (No model.)

To all whom it may concern:

Be it known that I, WILLIAM R. MORSE, a citizen of the United States, and a resident of Chicago, in the county of Cook and State of Illinois, have invented a new and useful Improvement in Letter-Openers, of which the following is a specification.

My invention relates to devices for cutting or opening envelopes, and has for its object to provide convenient means for so doing. This object I accomplish by means of the mechanism illustrated in the accompanying drawings, wherein—

Figure 1 is a plan view. Fig. 2 is a side view, and Fig. 3 is a vertical cross-section.

Like parts are indicated by the same letter in all the figures.

A is a bed containing the receptacle B.

C C' are standards adjustably secured to the bed by means of the vertical slots D D and bolts E E. On these standards are pivoted the roughened roller F, having at one end the pinion G, and on one of them is journaled the driving gear-wheel H, having the crank-handle J. The gear and pinion intermesh, so that by the rotation of the former the latter, with its roller, is driven. The surface of this roller is roughened or toothed, or provided with a file-finish, as indicated.

Along the upwardly-projecting edges of the sides of the bed are the ledges L L, which engage the grooves in the sides of the sliding frame N. The bed is provided with a cover O, which forms a bottom for the frame N, and is provided with a slot P, through which projects the upper edge of the roller F. The frame is provided with a sliding cross-piece or false side R, secured on the end of a rod S, which passes through a guide T in the front of the frame, and is held in any desired position by the set-screw U. The bearing of the gear-wheel is vertically adjustable on its standard C' by means of the slots and bolts X X. These parts could be greatly changed without departing from the spirit of my invention. The height of the roller can be adjusted by vertically adjusting the standards on which it is pivoted or journaled, and the

gear-wheel is vertically adjustable to permit the use of different sizes of wheels and to adjust the distance of the gear-wheel from the pinion.

The use and operation of my invention are as follows: When a package of envelopes has been received through the mail containing mail-matter, and it is desired to open them rapidly and without destroying or disfiguring the envelopes, they are placed within the frame, their edges solidly down upon the bottom thereof. Here they are squeezed into a compact mass by moving up the slide or false side, and in this condition they are firmly secured by setting the set-screw U. The frame is then moved up until the bottom of such package of envelopes is brought into contact with the upwardly-projecting edge of the roller. This roller is set rapidly in motion by means of the crank and wheel, and the package of envelopes is forced along over the same. In this process the lower edges of the envelopes are worn off and thus the entire package of envelopes opened.

I claim as new and desire to secure by Letters Patent—

1. A letter-opener provided with a rotating roughened roller which engages the edges of the envelopes.

2. A letter-opener provided with a rotating roughened roller, in combination with a movable letter-frame which passes thereover.

3. A letter-opener provided with a bed, a roughened roller journaled thereon, and a sliding letter-frame supported thereon.

4. A letter-opener provided with a bed, a rotating roughened roller journaled thereon, and a sliding letter-frame movable thereon and itself provided with a clamp to compress said letters into a mass.

5. A letter-opener provided with a letter-compressing frame containing a reciprocating slide, a bed whose top forms the bottom of said frame, and a roughened rotating roller which projects through said bottom, the frame adapted to slide on the bed and carry the envelopes over the roller.

6. In a letter-opener, the combination of a

bed with a roughened roller vertically adjustable journaled thereon, and a sliding letter-containing frame thereon.

7. In a letter-opener, the combination of a
5 false bottom letter-containing frame having
grooved sides, with a bed having ledges which
are received into such grooves and along
which such frame slides, and a rotating

roughened roller on such bed in the path of
such frame and the letter it contains.

Dated this 17th day of January, 1889.

WILLIAM R. MORSE.
